THERMIONIC TUBE

Earl L. Koch, Chicago, Ill., assignor, by mesne assignments, to Radio Patents Corporation, New York, N. Y., a corporation of New York

Original application March 21, 1931, Serial No. 524,254. Divided and this application July 3, 1934, Serial No. 733,547.

3 Claims. (Cl. 250—27.5)

This invention relates to improvements in thermionic tubes such as are employed in radio telegraphy and telephony.

This application is a division of application 5 Serial Number 524,254, filed March 21, 1931.

Thermionic tubes of the three element type which usually include an anode or plate, a cathode and a grid, are open to serious objection particularly with respect to capacity effects between 10 the grid and the plate. These effects are more pronounced when high frequency oscillations are employed.

An object of the invention is the provision of a thermionic tube in which this objection is obviated without the introduction of additional elements or circuits.

A further object of the invention is the provision in a transmitting, or power, electronic tube an anode or plate which further functions as a 20 part of the cooling system of the tube and which is statically shielded from the grid by the cathode.

Other objects will be apparent to those skilled in the art upon a perusal of this specification.

Referring to the drawing:

Figure 1 is a sectional elevation of the new and improved electronic tube,

Figure 2 is a transverse sectional view taken along the line 2—2 of Figure 1,

Figure 3 is a diagrammatic sketch showing the voltage gradient between a cathode and a plate when the cathode is heated to various degrees, and

Figure 4 is a diagrammatic sketch similar to Figure 3.

Referring to Figure 3 which shows graphically the voltage relation between the cathode and the anode or plate of a thermionic tube at various cathode temperatures, the oblique straight line 23 corresponds to an unheated cathode which is not emitting electrons. The curves 24, 25, and 35 26 represent increasing cathode temperatures, the cathode progressively emitting electrons at a greater rate as the heating increases. The progressively increasing deviation of these curves from the straight line 23 graphically illustrates 40 the effect usually termed the "space charge effect." The presence of innumerable electrons between the cathode and the plate results in this effect, the concentration of such electrons being greatest at the cathode or adjacent thereto. It will be 45 seen from the curve 25 that there is no voltage gradient adjacent the cathode at the cathode temperature corresponding to this curve, which is substantially horizontal, adjacent the cathode. The curve 26 corresponds to operating conditions 50 55 of the tube and it will be noticed that the con-

centration of electrons adjacent the cathode is sufficient to produce a zone about and in spaced relation to the cathode diagrammatically indicated by the dotted line 27. In this zone there is an actual negative voltage. In this specification 5 the zone within the surface 27 will be termed "the virtual cathode region."

According to the present invention, the grid is located about and surrounding the cathode structure and the cathode is preferably formed of 10 zigzag filaments 20, Figure 1, the grid 22 is preferably in the form of a cylinder surrounding and concentric with the cathode structure. When the tube is operating, the filament structure separates the grid from the plate by a cloud of electrons 15 which substantially reduce or nullify the capacity effect between the grid and the plate. The grid is preferably located within the virtual cathode region. When the cathode is cold, a definite capacity exists between the grid and the plate but 20 under operating conditions the cloud of electrons effectively reduces or nullifies this capacity. In the graphic illustration in Figure 4 the grid 22 represented by the dotted line is located very close to the cathode 20 so that it is well within the 25 virtual cathode region as shown by the voltage curve.

Referring to the tube, Figure 1, it is provided with a hollow cylindrical member 21 which forms the plate. This member is preferably constructed 30 of copper and is provided with nipples 52 which are located internally near each end of the member 21. By connecting hoses to the nipples 52 cooling water may be passed through the member 21 for cooling the tube while the same is in 35 operation. The ends 51 of the member 21 are each tapered to a knife edge which is sealed into inwardly directed necks 53 of the glass body 10 of the tube.

Inwardly extending collar 14 is positioned adjacent to and surrounding each end of the plate 21. These collars may be secured in any well-known manner to inwardly extending bosses 13 which form a part of the glass envelope 10. They extend inwardly beyond the bosses 13 and are 45 provided with holes or openings whereby a series of hooks 15 may be mounted. The hooks 15 support rings 16 of glass or other suitable insulating material and these rings form supports for a circumferential series of hooks 17 upon which 50 the cathode 20 may be strung in the form of a zigzag filament.

The grid or control element 22 which is preferably in the form of a short cylinder is located around and substantially concentric with the 55

cathode. The envelope 10 has a boss 19 formed in one side thereof which carries a metallic collar 18 which in turn supports the grid 22. A conductor 28 connected to the grid 22 extends 5 through the boss 19 and provides external means for connecting to the grid 22.

Leads 29 of the cathode may extend through the press 30 provided at a suitable position in 10 the glass envelope 10. A conductor 31 which is welded to one of the nipples 52 of the plate 21 provides a plate connection. This conductor together with its weld is positioned outside of the glass envelope 10. It is of course understood 15 that the cathode, the grid and the plate are enclosed in an evacuated vessel 10 which is comprised of both metal and glass.

It will be noted that the grid 22 is of substantially less length than that of the cathode. Therefore, the electron cloud not only shields the 20 interior of the grid 22 but it also shields the ends of the grid from capacity effects with the plate.

Although the invention has been disclosed in connection with the specific details of preferred 25 embodiments thereof, it must be understood that such details are not intended to be limitative of the invention except insofar as set forth in the accompanying claims.

What is claimed is:

1. A thermionic tube comprising, a cathode 30 having a zig-zag filament formed into an annular cage, a metallic water tube within and parallel to said cage and forming an anode, said metallic tube having straight extensions the ends of which form knife edges, a metallic sleeve sur-

rounding and closely adjacent to said cage and constituting a control element and a glass envelope sealed to said knife edges and forming, together with the metallic tube, a sealed enclosure for the cathode and the control element 5 through which a cooling fluid may pass in a straight line.

2. A thermionic tube comprising a glass envelope having inwardly directed necks at each end thereof, inwardly extending bosses located 10 near said necks, and a boss in the side wall thereof, a metallic tube having knife edged ends sealed into said necks and forming with said glass envelope a gas tight casing, said metallic tube forming an anode and serving as means for conducting 15 heat to a stream of water passing therethrough, a cathode comprised of a zig-zag filament formed into an annular cage positioned about and substantially concentric with said metallic tube, supports for said cage carried by said 20 inwardly extending bosses, and a metallic sleeve supported by the boss in said side wall and constituting a control element, the space between said control element and said cathode being less than that between the cathode and the anode. 25

3. A thermionic tube according to claim 1 in which the glass envelope is provided with inwardly extending bosses at each end which support the annular filament cage in space relation to the water tube forming the anode, and a third 30 inwardly extending boss spaced apart from said first bosses and supporting said sleeve closely adjacent to the cage forming said cathode.
